plugs P_1 and P'_1 adapted to be inserted in any of the jacks of the lines. While but one repeater is illustrated, it will be understood, of course, that as many repeaters will be 5 provided as traffic conditions may require. Each repeater comprises a pair of amplifiers herein illustrated as vacuum tube amplifiers A and A', although the amplifiers may be of any other type such as, for instance, the so called mechanical repeater. The amplifiers A and A' are provided with 10 input circuits 10 and 10' respectively, said input circuits being connected to potentiometers P and P'. The potentiometers consist 15 of resistance elements from various points of which connections are led through suitable controlling means to the input circuits of the amplifiers. The controlling means as illustrated, consists of a set of four controlling 20 relays 14, 15, 16 and 17, said relays being under the joint control of the repeater, and the line or lines with which it is associated. The potentiometers are inductively 25 connected through induction coils 11 and 11' with input bridges 12 and 12' connected across the line conductors extending to the plugs P_1 and P'_1 .

Individual to lines L_1 , L_2 and L_3 are balancing artificial lines N_1 , N_2 and N_3 . Similarly 30 artificial lines N_5 , N_6 and N_7 are individual to lines L_5 , L_6 and L_7 . In order to balance lines of the type of lines L_4 and L'_4 , an artificial line RN_4 common to all of said 35 lines, but individual to the repeater R is provided. Similarly an artificial line RN_8 individual to the repeater R is provided to balance lines of the type of lines L_8 and L'_8 . In order to select and connect to the repeater an artificial line suitable for 40 balancing a transmission line, to which the calling end of the repeater is connected, a selector switch SS is provided. This selector switch is of the type illustrated and described in the application of J. F. Toomey 45 and C. S. Demarest above referred to, and is arranged to actuate connecting relays 18, 19, 20, 21, 22, etc., to connect the proper artificial line to the repeater. In actual 50 practice, a similar arrangement would be provided for the answering end of the repeater, but in order to illustrate two types of selecting devices a set of selecting relays, including connecting relays 23, 24, 25, 26, 27, etc., is shown associated with the answering 55 end of the repeater. These selecting and connecting relays operate to select a suitable artificial line and connect the same to the repeater in the manner described in the application of C. S. Demarest above referred 60 to.

With this general description in mind, the invention may now be fully understood from a description of the operation of the apparatus. Assuming that it is desired to 65 interconnect lines L_1 and L_5 through the

repeater R, the plug P_1 is inserted in jack J_1 and the plug P'_1 is inserted in jack J_5 .

A circuit is thereby completed over sleeve contacts of plug P'_1 and jack J_5 from battery through the winding of relay 28, sleeve contacts of plug P'_1 and jack J_5 and winding of relay 29 to ground. Relay 28 is energized by current flowing through the above circuit, but relay 29 is marginal and is not energized by current flowing through the 75 high resistance of the winding of relay 28. Similarly a circuit is closed over the sleeve contacts of plug P_1 and jack J_1 from battery, winding of relay 30, sleeve contacts of plug P_1 , jack J_1 80 and winding of relay 31 to ground. Relay 30 is energized, but relay 31, like relay 29, is marginal and does not pull up over this circuit. The operator may now actuate a controlling key K by throwing it to the 85 right, whereupon battery is connected through a low resistance to the sleeve contact of plug P'_1 over contact 32 of said key. Relay 29 is now energized, and in pulling up its armature connects ground to the first 90 contact of switch SS over a circuit from ground, contact of relay 29, winding and back contact of relay 33, lower back contact and winding of relay 18 to the first contact of switch SS. Upon actuating key 95 K, a circuit was also closed from ground over the front contact of relay 28, contact 34 of key K, point 65, where the circuit divides, one path continuing through the winding of releasing magnet RM to battery, the other path continuing through the winding of relay 35, lower back contact of 100 relay 36, right hand back contact of test relay 37, winding of stepping magnet SM to battery. The releasing magnet RM is so 105 arranged that upon being energized it produces no effect upon the switch, but upon being released it actuates a mechanism whereby the switch is restored to normal, if it has been previously advanced out of its 110 normal or zero position. Upon the energization of relay 35 a circuit is closed over the front contact of said relay through the winding of relay 36 whereby said relay is 115 energized. Relay 36 at its upper front contact closes a circuit from ground over the upper front contact of relay 36, right hand back contact and winding of relay 38 to battery. Relay 38 is thereby energized and at its right-hand front contact closes a locking 120 circuit which extends over the left-hand back contact of test relay 37. Relay 38 at its left-hand front contact applies a ground to the zero contact of switch SS and all similar switches so that the test 125 relays of all other switches will be energized to prevent the actuation of such switches. The test relay 37 of switch SS is not, however, energized at this time as the stepping magnet SM upon being energized advances 130

- the switch one step so that its wiper 39 rests upon the first contact before relay 38 is energized. Relay 36 upon being energized also closes the circuit from ground over its upper 5 front contact and over the right-hand back contact and winding of relay 40 to battery. Relay 40 upon being energized at its right-hand front contact closes a locking circuit over the front contact of relay 28 to ground.
- 10 The operations resulting from the energization of relay 40 will be later described.
- Relay 36, upon being energized, at its lower contact opens the circuit previously traced through relay 35 and stepping magnet SM, so that relay 35 and stepping magnet SM are deenergized. The deenergization of relay 35 opens the circuit of relay 36 whereby the circuit previously traced through relay 35 and stepping magnet SM 15 is again closed, provided the test relay 37 has not been energized in the meantime. It will thus be seen that the relay 36 acts as a vibrating relay to open and close the circuit of stepping magnet SM whereby the switch is advanced step by step until its wiper rests upon a grounded contact. In the case now being described the first contact was grounded so that at the end of the first step a circuit was closed from ground 20 over the front contact of relay 29, winding and back contact of relay 33, lower back contact and winding of relay 18, first contact and wiper 39 of switch SS, through the winding of test relay 37 to battery.
- 25 Test relay 37 is thereby energized and at its left-hand contact it opens the locking circuit previously traced for the relay 38 whereby said relay is deenergized and removes the ground from zero contacts of the switches so that other switches may now be actuated if desired.
- 30 Relay 33, upon being energized, closes a locking circuit from battery over its left-hand front contact through the winding of said relay and over the contact of relay 29 to ground.
- 35 Relay 18, upon being energized, closes a locking circuit from battery through the winding of test relay 37, wiper 39 and first contact of switch SS, winding and lower front contact of relay 18, right hand winding of potentiometer controlling relay 14, 40 contact 34 of key K and contact of relay 28 to ground. Relays 37 and 18 are maintained energized over this circuit and relay 14 is energized. Connecting relay 18 at its upper contacts connects the artificial line 45 N₅ to the repeater so that the line L₅ is now balanced with respect to the input bridge 12' of the repeater by means of artificial line N₅.
- 50 Returning now to relay 40, said relay upon being energized, at its middle front contact connects battery through a low resistance to the sleeve contact of plug P₁ so that relay 31 now receives sufficient current to energize its winding. A circuit is now closed from ground over the front contact 55 of relay 31, resistance 64, winding and lower back contact of relay 23, back contact of relay 41, middle winding of relay 14, resistance 42, back contact and winding of relay 43, left-hand front contact of relay 40, and front contact of relay 30 to battery. Relays 23, 14 and 43 are energized over this circuit. Relay 23, upon being energized, at its lower front contact closes a locking circuit from ground, front contact of relay 31, resistance 64, winding and lower front contact of relay 23, resistance 44 and winding of relay 45 to battery. Relay 45 is energized over this circuit and at its upper front contact closes a circuit through winding of relay 41 to open the initial energizing circuit of connecting relay 23.
- 60 It will be understood that a connecting relay such as 23, corresponding to the line L₁ will be provided for each repeater, and that a corresponding relay such as 41 will also be provided for each repeater. The relay 45 at the same time that it closes the circuit of relay 41 closes the circuits of similar relays corresponding to the other repeaters so that the circuits of the connecting relays of all other repeaters are thereby held open to prevent a false selection. Relay 43, upon being energized, at its contact disconnects its winding from the selecting circuit 65 previously traced through the windings of relays 43, 14 and 31, at the same time locking itself over its front contact.
- 70 Relay 14, upon being energized, at its middle contact closes a locking circuit from ground through the winding of relay 46, left-hand winding and middle contact of relay 14, left-hand front contact of relay 40 and front contact of relay 30 to battery. Potentiometer controlling relay 14 is now 75 energized and locked up, and at its left and right-hand front contacts connects the first points of the potentiometers P and P' to the grids of the amplifiers A and A'. Relay 46, which was energized by the locking circuit above traced performs no useful function at this time.
- 80 Returning to the relay 40, it will be noted that said relay by means of its middle and left-hand contacts performs functions 85 similar to those performed by the contacts 32 and 34 of the key K. This arrangement is provided in order that the initiation of the selection for the answering end of the repeater shall be delayed for a short time 90 with respect to the initiation of the selection at the calling end of the repeater so as to eliminate the possibility of a false selection.
- 95 It will now be seen that lines L₁ and L₅ 95

are interconnected through the repeater R, said lines being balanced by artificial lines N₁ and N₅ which are connected to the answering and calling ends of the repeater 5 respectively by means of connecting relays 23 and 18. Further, the grids of the amplifiers A and A' are connected by means of the potentiometer controlling relay 14 to the first point of potentiometers P and P', 10 thus securing the proper amount of transmission gain for this particular connection. If for any reason the amplifiers should give too great a degree of amplification so that singing results, the operator may throw 15 the key K to the left, instead of the right, thereby closing contacts 47, 48 and 49. Contacts 47 and 48 are connected in parallel to contacts 32 and 34, and consequently result in the same sequence of operations as al- 20 ready described, so that the same artificial lines will be connected with the repeater and the same setting of the potentiometer will be secured. The closure of contact 49, how- 25 ever, results in the completion of a circuit from ground, front contact of relay 28, contact 49 of key K and windings of relays 50 and 51 to battery. Relay 51, upon being energized, removes a short circuit from a re- 30 sistance 52 serially connected in the out- 35 put circuit 13 of amplifier A' and closes a shunt connection across said output circuit through the resistance 53. Similarly relay 50 removes a short circuit from about resistance 52' in output circuit 13' 40 of amplifier A and closes a shunt across said circuit through the resistance 53'. These circuit changes result in reducing the transmission gain due to the repeater by an amount sufficient to prevent singing. In 45 actual practice the resistances may be ad- justed so as to secure a decrease in trans- mission equivalent to about five miles of standard cable.

It will be noted that the connection above 45 described results in the energization of potentiometer controlling relay 14 only. If, however, the connection had been made between lines L₁ and L₆, upon operating the key K a relay 63 corresponding to line L₆ 50 would have been energized, thereby applying ground to the second contact of the switch SS so that said switch would have been advanced two steps and would have rested with its wiper 39 upon its second contact, thereby energizing connecting relay 19 55 to connect artificial line N₆ to the repeater. Relay 19, at its lower contact would have closed a locking circuit extending through the right-hand winding of potentiometer 60 controlling relay 15 instead of relay 14, as previously described. On the other hand, relay 31 would have been energized as before, so that the connecting relay 23 would have operated to connect artificial line N₁ 65 to the repeater and a momentary circuit

would have been closed through the second winding of relay 14 as already described. Relay 14 would thereby be energized and complete a locking circuit through its left-hand winding and the winding of relay 46, 70 as already described. Similarly relay 15, upon being energized, closes a locking circuit from ground through the winding of relay 54, through the left-hand winding and middle contact of relay 15, and over the left-hand contact of relay 40 and contact of relay 30 to battery. The energization of relays 46 and 54 would result at this time in no useful operation. The energization of potentiometer controlling relay 15 would result in the connection of the second point of the potentiometers P and P' to the grids of the amplifiers over the right-hand and left-hand contacts of said relay 15 were it not for the fact that 80 potentiometer relay 14 is also energized so that the grids are disconnected from the second points of the potentiometers by the right-hand and left-hand contacts of relay 14 and connected over the corresponding 85 front contacts to the first points of the potentiometers.

It will thus be seen that when two adjacent potentiometer controlling relays are 90 actuated the potentiometer connection will 95 be determined by the lower relay of the two, the upper relay being without effect.

If the connection had been between line L₁ and line L₈, the actuation of the key K would have resulted in the energization of 100 relay 55, whereby the fourth contact of the switch SS would have been grounded, and upon the actuation of the switch, connecting relay 21 would have been energized to connect the artificial line RN₈ to the repeater 105 to balance the line L₈. Relay 21 at its lower front contact would have closed a circuit through the right-hand winding of relay 17, thereby energizing said relay so that a locking circuit would have been closed 110 through the winding of relay 56, left-hand winding and middle contact of relay 17, left-hand contact of relay 40 and contact of relay 30 to battery, energizing relay 56 and holding relay 17 energized independently of its right-hand winding. Relays 14 and 46 would have been energized as before. Relay 14 at its right-hand and left-hand front contacts would have connected the first 115 points of the potentiometers to the grids were it not for the fact that the joint action of relays 46 and 56 results in the closure of a circuit from ground over the right-hand contact of relay 56, front contact of relay 46 and winding of relay 57 to battery. Relay 57 is energized over this circuit, and at its right-hand and left-hand back contacts opens the connection from the contacts of relay 14 to the grids of the amplifiers. Said relay 120 125 57 at its front contacts connects the grids 130

to the second points of the potentiometer. The actuation of the right-hand and left-hand contact of relay 17 is without effect because the connection thereby closed from the fourth points of the potentiometers is opened at the contacts of relay 14.

5 The same result would have been secured had the connection been between lines L_1 and L'_8 as the actuation of the controlling key K 10 would have resulted in the energization of relay 58, thereby connecting ground to the fifth contact of the switch so that the relay 22 would have been energized. Relays 21 and 22 have their lower contacts connected 15 in parallel to the right-hand winding of relay 17, so that the same series of operations results as just described.

If the connection had been between lines L_1 and L_7 , the actuation of the controlling key 20 would have resulted in the energization of relay 59, thereby connecting ground to the third contact of the switch so that relay 20 would have been energized to connect artificial line N_7 to the repeater, and at its lower 25 front contact to close a circuit through the right-hand winding of potentiometer controlling relay 16. The connection to line L_1 would have resulted in the energization of potentiometer relay 14 as already described.

30 Relay 16, upon being energized would have completed a locking circuit from ground through the winding of relay 60, left-hand winding and middle contact of relay 16, left-hand contact of relay 40 and contact of relay 30 to battery. Relays 46 and 60 would now 35 be energized, thereby completing a circuit from ground over the front contact of relay 60, front contact of relay 46 and through the winding of relay 57 to battery.

40 Relay 57 is now energized and at its front contacts connects the second points of the potentiometers to the grids of the amplifiers. The actuation of the controlling contacts of 45 relays 14 and 16 produces no result as the grids are now directly under the control of relay 57.

Without attempting to further describe the various connections with their possible results, it is sufficient to say that when any 50 two lines are connected, one or two of the potentiometer controlling relays are actuated. If only one relay is actuated its right-hand and left-hand front contacts control the connection of the grids to the corresponding 55 points of the potentiometer. If two potentiometer controlling relays are actuated, the connection between the grids and the potentiometer will be controlled by the contacts of the lower relay only, except when 60 relays 14 and 17, 14 and 16, or 15 and 17 are actuated at the same time. In the latter case, a circuit is closed over the left-hand contact of relay 56 and the contact of relay 54 through the winding of relay 61 to battery. 65 Relay 61 at its front contacts connects the

grids to the third points of the potentiometer. In the other two cases the relay 57 is energized in the manner already described and connects the grids to the second points of the potentiometers. The only instance in which the fourth points of the potentiometer will be connected to the grids is when the relay 17 is actuated alone.

Upon withdrawing the plugs of the repeater circuits from the jacks, the apparatus 70 will be restored to normal. This operation may be understood from a consideration of the connection previously described between lines L_1 and L_5 . Upon withdrawing the plug P'_1 from the jack J_5 relays 28 and 29 75 are deenergized. Upon the deenergization of relay 28 the circuit of the releasing magnet RM of the switch SS is broken at the contact of said relay and the switch SS is thereby restored to normal, breaking the circuit 80 previously traced through relays 37, 18 and the right-hand winding of relay 14. Relays 37 and 18 are accordingly deenergized. Upon the deenergization of relay 28 the locking circuit previously traced through relay 40 85 is broken, and relay 40 is deenergized. Relay 29 upon being deenergized at its contact opens the locking circuit of relay 33, thereby restoring said relay to normal. Upon withdrawing plug P_1 from jack J_1 relays 30 and 31 are 90 deenergized. Relay 30 at its contact opens the locking circuit of relay 43 and also opens the locking circuit of the left-hand winding of relay 14 and the winding of relay 46. Relays 14 and 46 are thereby deenergized and the 95 potentiometer controlling apparatus is restored to normal. Relay 31, upon being deenergized, opens the locking circuit previously traced through relays 23 and 45, thereby deenergizing said relays. Relay 45 in turn 100 opens the circuits of the relay 41 and the similar relays corresponding to the other repeaters. In case the key K had been thrown to the left, thereby operating relays 50 and 51 said relays would be restored to normal by 105 the deenergization of relay 28, so that the artificial lines controlled by said relays 50 and 51 for reducing the transmission efficiency of the repeater, will be restored to normal.

It will be seen that by means of this invention, the transmission gain due to the connection of two transmission circuits through a repeater may be automatically determined by means of the particular circuits connected, thereby eliminating the cost of the potentiometer regulating key, which, with the cost of its installation and cabling is an expensive feature in the organization heretofore used. Moreover, the capacity of the switchboard key shelf would not be reduced so much as at 115 present, as the single lever, repeater control key required by the arrangement just described would take much less room than the potentiometer regulating key heretofore used. Furthermore, no attention need be given by 120 125 130

the operator to the selection of the proper adjustment for each connection, so that the work required of the operator is considerably reduced.

5 While the invention has been disclosed as embodied in certain forms which are considered desirable, it will be understood that it may be embodied in many widely different organizations without departing from the 10 spirit of the invention.

What is claimed is:

1. A transmission circuit for transmitting 15 signaling currents, terminal apparatus with which said circuit may be associated, and means operating automatically to so vary the transmission efficiency of said circuit, in accordance with the transmission requirements with respect to the signaling currents of any type of terminal apparatus with 20 which said circuit is associated, that the total transmission equivalent of said transmission circuit and terminal apparatus will be substantially constant regardless of the type of terminal apparatus associated with 25 the transmission circuit.

2. A transmission circuit for transmitting signaling currents, a plurality of terminating lines with which said transmission circuit may be associated, and means controlled 30 by said terminating lines to so adjust the transmission efficiency of said circuit, in accordance with the transmission requirements with respect to signaling currents of the line with which it is associated, that the total 35 transmission equivalent of the circuit and line will be substantially constant regardless of the line with which the transmission circuit is associated.

3. A repeater circuit, terminal apparatus 40 with which said repeater circuit may be associated, and means operating automatically to so control the transmission gain of said repeater circuit, in accordance with the transmission requirements of the terminal 45 apparatus with which it is associated, that the total transmission equivalent of the repeater and associated terminal apparatus will be substantially constant regardless of the type of terminal apparatus associated 50 with the repeater.

4. A repeater circuit, a plurality of transmission lines with which said repeater circuit may be associated, and means controlled 55 by said transmission lines to so adjust the transmission gain of said repeater circuit, in accordance with the transmission requirements of the line with which it is associated, that the total transmission equivalent of the repeater circuit and associated line will be 60 substantially constant regardless of the character of the line associated with the repeater.

5. A repeater, means to determine the amplification of said repeater, terminal apparatus with which said repeater may be asso-

ciated, and means to automatically control said amplification determining means in accordance with the transmission requirements of the terminating apparatus with which the repeater is associated.

70

6. A repeater, adjustable means to determine the amplification of said repeater, a plurality of transmission lines with which said repeater may be associated, and means controlled by said transmission lines to adjust said amplification controlling means in accordance with the requirements of the line with which the repeater is associated.

75

7. A repeater comprising an evacuated tube provided with a controlling electrode, a potentiometer associated with said electrode, terminating apparatus with which said repeater may be associated, and means for automatically adjusting the potentiometer in accordance with the requirements of the terminating apparatus with which the repeater is associated.

80

8. A repeater comprising an evacuated tube including a controlling electrode, a potentiometer associated with said electrode, a plurality of transmission lines with which said repeater may be associated, and means controlled by said transmission lines to adjust said potentiometer in accordance with the requirements of the transmission line with which said repeater is associated.

90

9. A repeater circuit, a plurality of transmission lines with which said repeater circuit may be associated, a plurality of artificial lines for balancing said transmission lines, means for selecting an artificial line to balance the transmission line with which said repeater circuit is associated and means to automatically control the transmission efficiency of said repeater circuit in accordance with the requirements of said transmission line.

100

10. A repeater circuit, a plurality of transmission lines with which said repeater circuit may be associated, a plurality of artificial lines to balance said transmission lines, and means controlled by said lines for selecting an artificial line to balance the transmission line with which the repeater circuit is associated and for controlling the transmission efficiency of said repeater circuit in accordance with the requirements of said transmission lines.

110

11. A repeater circuit, a plurality of transmission lines with which said repeater circuit may be associated, a plurality of artificial lines to balance said transmission lines, and a selecting switch for controlling the selection of an artificial line to balance the transmission line with which said repeater circuit may be associated and for controlling the transmission efficiency of said repeater circuit in accordance with the requirements of the transmission line with which the repeater circuit is associated.

120

125

130

12. A repeater circuit, a plurality of transmission lines with which said repeater circuit may be associated, a plurality of artificial lines to balance said transmission lines, 5 and a relay selecting circuit for controlling the selection of an artificial line to balance the transmission line with which said repeater circuit may be associated and for controlling the transmission efficiency of said repeater circuit in accordance with the requirements 10 of the transmission line with which the repeater circuit is associated.
13. A repeater comprising an evacuated tube having a controlling electrode, a potentiometer in circuit with said electrode, a plurality of relays for variably controlling the connection between said potentiometer and said electrode, a plurality of lines with which said repeater may be associated, and means 20 to selectively energize one of said relays in accordance with the line with which the repeater is associated.
14. A repeater comprising an evacuated tube having a controlling electrode, a potentiometer in circuit with said electrode, a plurality of lines with which said repeater may be associated, certain of said lines being grouped, and a plurality of relays for variably controlling the connection of said potentiometer to said electrode, certain of said relays being individual to groups of lines and responsive to the association of the repeater with a line of the group to control said connection.
15. A plurality of transmission lines, a repeater circuit for interconnecting said lines, and a plurality of relays for controlling the transmission efficiency of said repeater circuit, each relay having two energizing circuits controlled by the association of opposite ends of the repeater circuit with transmission lines.
16. A plurality of transmission lines of different types, a repeater circuit for interconnecting said lines, a plurality of relays corresponding to different types of lines for controlling the transmission efficiency of said repeater circuit, a circuit for each relay controlled by the association of one end of the 50 repeater circuit with a transmission line, and another circuit for each relay controlled by the association of the opposite end of the repeater circuit with a transmission line whereby one relay will be energized if the repeater circuit is associated with lines of 55 the same type, and two relays will be energized if the repeater circuit is associated with lines of different types.
17. A transmission circuit, a plurality of terminating lines with which said transmission circuit may be associated, means controlled by said terminating lines to adjust the transmission efficiency of said circuit in accordance with the requirements of the line with which it is associated, and means controllable at will to vary the adjustment thus obtained.
18. A transmission circuit, a plurality of terminating lines with which said circuit may be associated, and a plurality of relays 60 for variably controlling the transmission efficiency of said circuit, said relays being selectively operated in accordance with the terminating line with which the circuit is 65 associated.
19. A transmission circuit, a plurality of terminating lines with which said circuit may be associated, certain of said lines being grouped, and a plurality of relays for variably controlling the transmission efficiency of said circuit, certain of said relays being individual to groups of lines and responsive to the association of said circuit with a line of the group to control said connection.
20. A repeater, a plurality of transmission lines of different types with which said repeater may be associated, and means controlled by the line with which said repeater is associated for determining the amplification of the repeater, said means operating so that when the repeater is associated with two lines of different types, the transmission gain obtained will be approximately a mean between the values of gain suitable for the two 95 types.

In testimony whereof we have signed our names to this specification this ninth day of October, 1917.

JOHN F. TOOMEY.
CHARLES S. DEMAREST.
